GRAFTON W. APPLER, OF LYONS, NEW YORK.

ELECTRIC GAS-IGNITER FOR HOT-WATER-CIRCULATING SYSTEMS.

1,032,727.

Specification of Letters Patent. Patented July 16, 1912.

Application filed June 21, 1911. Serial No. 634,468.

To all whom it may concern:

Be it known that I, GRAFTON W. APPLER, of Lyons, in the county of Wayne, in the State of New York, have invented new and useful Improvements in Electric Gas-Igniters for Hot-Water-Circulating Systems, of which the following, taken in connection with the accompanying drawings, is a full, clear, and exact description.

This invention relates to certain improvements in electric gas igniters for water heaters forming the basis of a hot water circulating system in which are connected one or more faucets and suitable mechanism controlled by the opening and closing of the faucet or faucets for regulating the flow of gas to the burner. In all of the heating systems of this character now in common use, it is customary to ignite the gas at the burner by means of a continuously burning pilot light which is connected to the main gas supply pipe by a bypass around the main valve. It frequently happens that the building in which the heater is located will be vacated for a considerable period of time particularly during the summer months without shutting off the pilot light which results in an expensive and unnecessary waste of gas, while on the other hand in some instances either when the house is vacated or occupied, the pilot light has been blown out by sudden drafts of air or cut off by the temporary closing of the gas main or pipe leading to the building in which the heater is installed so that when the gas is turned on in the mains, it will not only be allowed to escape through the pilot light jet without burning but when any of the faucets are opened in any part of the building, a considerably larger volume of gas is allowed to escape from the burner into the adjoining room and in time will permeate the whole building. This, of course, renders the use of a pilot light extremely dangerous both from inhalation and explosion of gas, and the main object of my present invention is to entirely eliminate the pilot light and its accompanying disadvantages and dangers by the use of an electric igniting device which is automatically brought into action to ignite the gas immediately upon the opening of any one or more of the faucets by which the gas supply to the burner is controlled, said igniting device

being also automatically deenergized by the closing of the faucet or faucets, thereby conserving the source of electric energy.

Another object is to provide thermostatic means for regulating the temperature of water by regulating the supply of gas to the burner and automatically controlling its ignition.

A still further object is to provide means in proximity to each faucet for indicating the condition of the spark and circuit so that if the current is not sufficiently strong to produce the spark, such fact will be made apparent or indicated to the operator at the time the faucet is turned, thus warning the operator to shut off the water at once and avoid the escape of gas until the current or spark is restored to its working condition.

Other objects and uses will be brought out in the following description.

In the drawing I have shown a diagrammatic view of a water heater, burner and part of a hot water circulating system together with my improved gas igniting mechanism associated therewith.

The water heater forming the basis of a hot water circulating system may be of any desired form, size or construction but usually comprises a relatively long coil of pipe arranged in an upright position within a suitable casing —A— directly over a gas burner —B— of sufficient capacity to heat the water to any desired degree while passing through the coil. Water is supplied to one end (usually the upper end) of the coil from any available source through a pipe —a— in which is connected a cylinder —D— having inlet and outlet ports —b— and —b'— arranged one in advance of the other lengthwise of the cylinder. A piston valve —C— is movable in the cylinder and is normally held between the ports by a retracting spring —c— so as to normally cut off the passage of water through the pipe —a—. The opposite or lower end of the heater coil is connected by a pipe —1— to one end of a tube —2— containing a thermostatic bar —3—, the opposite end of said tube being connected by a pipe —4— to a water circulating system of pipes —5— having one or more faucets —6— connected thereto.

A gas pipe —7— leading from any available source of supply is connected to a valve

2
chamber —8— containing a valve —9— which is normally held in its closed position by a spring —10—, the valve chamber —8— being connected by a pipe —11— to an auxiliary valve chamber —12— containing a valve —13— which is normally held in its open position by a spring —14—. The auxiliary valve chamber —12— is connected by a pipe —15— to the burner —B— for supplying gas thereto when the valve —9— is opened.

10 The piston valve —C— is provided with a valve stem —16— extending through a gland in one end of the cylinder —D— and 15 adapted to engage a similar valve stem —17— on the valve —9— for opening the latter valve when the piston valve —C— is moved from its normal position against the action of the spring —c—.

20 When the faucets in the hot water circulating system are all closed, the pressure at opposite sides of the piston valve —C— is equal, thereby holding the piston valve in its closed position for cutting off the flow of 25 water through the pipe —a— but when any one or more of the faucets are opened relieving the pressure on the inside of the piston valve —C—, the greater pressure at the opposite side moves said piston against the 30 action of the spring —c—, thereby forcing its rod against the adjacent end of the coaxial valve rod —17— for opening the valve —9— and allowing the gas to flow from the pipe —7— through the valve chambers —8— 35 and —12— and pipe —15— to the burner.

Arranged in close proximity to and preferably in the path of escape of the gas from the burner —B— is an electric spark plug or terminals —20— forming a part of an 40 electric sparking circuit —21— having the usual spark coil —22—. An electric switch —23— is also connected in the primary circuit and is adapted to be closed by the opening of the water valve —C—, energizing the 45 sparking circuit and producing a spark at the terminals —20— for igniting the gas simultaneously with the opening of the water valve —C— and gas valve —9—. This 50 electric switch may be of any suitable construction capable of being operated by the water controlling valve or any of the other movable parts actuated thereby and in this instance I have shown a pair of terminals arranged in close proximity to and parallel 55 with the piston rod —16— and insulated from each other and have provided the piston rod with a contact member —24— slideable across and upon the terminals to bridge the intervening gap and close the circuit 60 when the piston valve —C— is shifted from its normal position by the opening of one of the faucets —6—, it being understood that the contact piece —24— is normally withdrawn toward the cylinder —D— to the 65 corresponding side of the intervening space

between the terminals so that the switch is normally open. In like manner I have shown a normally closed electric switch —25— connected in the same primary circuit preferably in series with the switch —23— and adapted to be operated by the expansion and contraction of the thermostatic bar —3— which is surrounded by the heated water passing through the tube —2—. This switch —25— is very similar to the switch —23— in that it is provided with a pair of terminals arranged parallel with and in close proximity to a stem —26— on the outer end of the thermostatic bar —3—, said stem being provided with a contact piece —27— normally bridging the intervening space between the terminals of the switch —25— to close this portion of the igniting circuit.

70 The stem —26— of the thermostatic bar —3— is coaxial with and adapted to abut against a similar stem —28— of the valve —13— so that when the bar —3— expands by the gradually increasing heat of the water passing through the tube —2—, the stem —26— will be pressed against the stem —28— to close or partially close the valve —13— for reducing or cutting off the supply of gas through the pipe —15— to the burner —B—, thereby regulating the temperature of the water to a predetermined degree and this temperature may be increased or diminished by simply adjusting the bar —3— endwise by means of an adjusting screw —30— as shown at the right 80 of the thermostatic tube —2—.

85 Associated with each of the faucets —6— is an electrically operated signal which, in this instance, consists of a buzzer —31— electrically connected by wires —32— in the same circuit with electric switches —35— and —36— in such manner that it will be energized only when the water is flowing through the adjacent faucet under which 90 conditions the gas is flowing through the 95 burner —B—.

100 The object of the indicator is to enable the operator to determine whether or not the sparking circuit or current is in proper working condition for producing the desired circuit at the burner and if for any reason the indicator should fail to operate, it will warn the operator at once to shut off the faucet and thereby cut off the supply of gas to the burner to prevent escape 115 of such gas into the room in which the heating apparatus is installed. The indicator, however, is not absolutely essential to the operation of my improved igniter and is only introduced as a precautionary measure 120 to further reduce liability to explosion or other dangers arising from escape of gas.

125 Under normal conditions or when any water is being drawn from either of the faucets, the supply of water to the heater 130

and also the supply of gas to the burner are cut off but when one or more of the faucets are opened, the inequality of pressure on opposite ends of the piston —C— produced 5 thereby will cause said piston to be moved endwise against the action of the spring —c—, thereby opening the gas valve —9— to permit the flow of gas to the burner —B— and at the same time operating the switch 10 —23— to close the sparking circuit for igniting such gas at the burner. At the same instant that the gas is ignited, the water is heated and allowed to flow through the 15 thermostatic tube —2—, thereby enveloping the thermostatic bar —3— and passing it through the pipe system —5— and open faucets —6—.

The heated water passing through the tube —2— operates to expand the thermostatic bar —3— endwise, thereby opening the electric switch —25— and tending to close the auxiliary gas valve —13— against the action of the spring —14— to reduce the supply of gas to the burner, thereby 25 lowering the heat and operating to maintain a more uniform temperature of water and if for any reason the water should exceed the predetermined degree, the bar —3— will expand still more or sufficiently to entirely 30 close the valve. Now, if one of the faucets should remain open with the gas supply cut off in the manner just described, it is evident that the temperature of the water will lower and cause the thermostatic bar —3— to contract to again open the auxiliary valve 35 —13— and at the same time will close the electric switch —25— to reignite the gas, it being understood that while the thermostatic bar is operating to control the temperature 40 of the water by regulating the supply of gas, the water valve —C— remains open and maintains the switch —23— in its closed position so that the temperature of the water is regulated solely by the thermostatic bar —3— while the water supply to the heater and main gas supply to the burner, are controlled by the action of the piston —C—.

The electric indicators for the several 50 faucets are shown as connected in parallel, while the electric switches —35— and —36— are shown as connected in series, the switch —35— being normally open and adapted to be closed instantly by the operation of the 55 water valve caused by the opening of one of the faucets and may remain closed as long as the faucet is open. Under such conditions the electric switch —36— is normally closed but is adapted to be opened immediately upon the heating of the water sufficient 60 to operate the thermostat, said switch being alternately opened and closed, while the faucet is opened by the variable action of the thermostat so that if the buzzer operates 65 under this closing of the circuit, it will indi-

cate that the current is sufficient to energize the spark coil and thereby produce the desired spark at the burner.

What I claim is:

1. In a water heating system, a water 70 heater, a cold water supply pipe leading to the heater, a hot water distributing pipe leading from the heater, a gas burner, a gas supply pipe for the burner, a valve in the cold water supply pipe operated by different pressures at opposite sides thereof to control the water supply to the heater, a normally closed valve and a normally open valve both in the gas supply pipe, means operated by the water controlling valve for 75 opening the normally closed valve for automatically permitting the passage of gas through the normally open valve to the burner, an electric igniting device for the gas including a switch operated by the 80 water controlling valve, a thermostatic bar in the water distributing pipe, means actuated by said thermostatic bar for closing the normally open gas regulating valve, and means including a normally closed electric 85 switch forming a part of the igniting device and operated by the thermostatic bar for automatically controlling said igniting device and thereby controlling the temperature of the water while the first named 90 switch remains closed, said valves and thermostatic bar being arranged in alinement to operate in the same general direction.

2. In combination with a water circulating system including therein a water heater 100 and a water faucet, a normally closed valve in the side of the system connected to the inlet of the heater and adapted to be opened by varying pressures at opposite sides thereof produced by the opening of the faucet, a 105 gas burner for the heater, means operated by the valve for controlling the supply of gas to the burner, an electric igniting device for the gas including an electric circuit having a normally open switch adapted to be 110 closed by the opening of the valve, an electric signal circuit deriving current from the same source of electric energy as the first named circuit and having a signal in proximity to the faucet and including therein a 115 normally open electric switch adapted to be closed by the opening of said valve simultaneously with the closing of the first named switch whereby the operator of the faucet may determine whether or not the igniting 120 device is sufficiently active to ignite the gas.

3. In combination with a water circulating system including therein a water heater and a faucet, a gas burner for heating the water in the heater, a valve controlling the supply of gas to the burner, automatic means controlled by the opening and closing of the faucet for controlling the operation of the valve, a thermostat within a part of the water circulating system influenced 125 130

by varying temperatures of water therein, means actuated by the thermostat for separately controlling the operation of said valve, an electric igniting device for the gas including an electric circuit having a switch operated by the thermostat, and an electric signal circuit deriving current from the same source of electric energy as the first named circuit and having its signal in prox-

imity to the faucet, said switch being also 10 operated by the thermostat.

In witness whereof I have hereunto set my hand on this 1st day of June 1911.

GRAFTON W. APPLER.
